UNITED STATES PATENT OFFICE.

ISAAC W. NUMAN, OF CANTON, OHIO.

PUMP.

SPECIFICATION forming part of Letters Patent No. 334,605, dated January 19, 1886.

Application filed April 6, 1885. Serial No. 161,313. (No model.)

To all whom it may concern:

Be it known that I, ISAAC W. NUMAN, a citizen of the United States, residing at Canton, in the county of Stark and State of Ohio, have 5 invented certain new and useful Improvements in Pumps, of which the following is a specification, reference being had therein to the accompanying drawings.

Figure 1 is a side elevation of a pump containing my improvements. Fig. 2 is a vertical longitudinal section. Fig. 3 is a side view of a pump provided with a support of a somewhat different form from that shown in Fig. 1. Fig. 4 is a detail view enlarged.

15 My invention relates to certain improvements upon that class of cheap portable pumps which are usually made from tin or other sheet metal, whereby they may be more cheaply constructed and made to operate more satisfactorily.

In the drawings, A represents the working-barrel, which is surrounded or partially surrounded by the air-chamber B, there being a passage-way, a, between the two, covered by 25 the outwardly-working valve b. This valve is formed of a small cone or funnel-shaped valve-seat, b', attached to the working-barrel, so that it surrounds the aperture a, in which seat lies the ball-valve b². The larger end of 30 the seat is outward, thus allowing the water to pass from the tube A into the chamber B as the piston descends, but prevents its being forced back as the motion of the piston is reversed.

35 R is a plug or stopper screwed into an opening in the outer wall of the chamber B, opposite the valve b. By removing the plug R the valve between the pump and air-chamber is exposed, and may be cleansed from dirt or obstructions—an operation which has been impossible in pumps as heretofore constructed.

It will be understood that a removable plug, R, may be used in combination with valves of other constructions than that shown, permitting ready access to such valves for the purpose of repairing or cleaning; but the valve shown possesses advantages, in that it may be employed for pumping hot liquids, which would be injurious to valves of leather or 45 gum. The plug may be depended upon to retain the ball b² within its seat; or the seat may be provided with a confining-cage, if desired.

C is a valve situated in the lower end of the working-barrel and adapted to allow the passage of water into the cylinder A, and to close 55 as the piston descends, causing the water to pass out into the air-chamber through opening a.

D is the piston, and E the piston-rod, which latter gradually tapers upwardly, for a purpose to be described, and is provided at its upper end with a handle, F, by which it is worked.

The upper end of the working-barrel is screw-threaded at g, and is closed by a cap, 65 G, engaging with the screw-threaded portion of the working-barrel. The opening in cap C, through which the piston-rod passes, is of tapering form, it being of greater diameter at the lower end than it is at the top. The relative sizes of the tapering aperture in cap G and the tapering piston-rod are such that when the piston-rod and piston are raised to about the highest point the piston-rod completely fills the aperture in the cap and prevents any 75 waste water which may have passed above the piston from splashing or being forced out of the top of the pump, there being a passage, H, through which such waste water is conveyed back into the vessel in which the pump 80 is placed.

By constructing the piston-rod and cap G in the manner described I am enabled to dispense with any packing around the piston-rod where it passes through the cap, and yet prevent the water above the piston from being forced out of the top of the pump, thus making a pump which operates satisfactorily at a very small cost.

I is a valve situated in the lower part of the 90 air-chamber B. It operates, when the pump is in operation, simply to close the opening J in the bottom of the air-chamber; but it may be lifted after the pump has ceased operation, to allow all water to drain out from the air-chamber of the pump—an operation which has been attended with considerable difficulty in pumps of this character as heretofore constructed.

In order to better permit the valve I to be 100 raised, I ordinarily provide it with a stem, i, projecting below the bottom of the air-chamber, and provided at its lower end with a head or enlargement to retain it in place.

k is a tube, preferably of metal, extending from near the bottom of the air-chamber through the top thereof, and adapted to have the hose *L* attached to its upper end.

5 Pumps of the above-described character are usually inserted into small vessels—such as tubs, pails, &c.—containing water, and are frequently provided with supports upon which the foot is placed in order to hold the pump steady while the piston is being worked up and down; but it is often found, when such support is rigidly and permanently connected with the pump-barrel, that when the pump rests upon the bottom of the water-vessel the foot-support does not reach the ground, and is therefore not at all times operative. I have shown an adjustable support which effectually overcomes this difficulty.

10 *M* is a rod or bar, carrying the foot-piece *N* at its lower end. It is adjustably connected to the pump by means of a holder comprising two arms, *O' O'*, permanently fastened to the pump at different points vertically, considerably distant from each other, and carrying a 15 tubular receiver or receivers, *P*, in which rests the rod. In the form shown in Figs. 1 and 2 the tubular receivers are connected with the said parts *O' O'* by means of a vertical bar or plate, *O*, which, however, may be dispensed with, as will be hereinafter described. I also combine with the said parts *O' O'* and the tubular receivers a clamp having as one of its parts a screw or bolt, said clamp engaging directly with the rod *M*. Still referring to Figs. 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255
